CONTAINER

Leo Morgan, Toronto, Ontario, Canada

Application September 11, 1948, Serial No. 48,847

2 Claims. (Cl. 224—45)

1

The present invention relates to a container of the type used in displaying and as a carrier for bottled beverages and the like.

Containers formed of compressed paper stock, such as cardboard, shaped to serve as a carrier for displaying and carrying soft drink bottles are well known and widely used. Such containers ordinarily are designed in two half sections, each half section being formed in the shape of a partially enclosed tray adapted to receive several bottles. Each half section is formed with a carrying handle and the two half sections are joined together and suitable reinforced, such as by metal reinforcing members, to provide a relatively sturdy structure which may be carried conveniently.

An important object of this invention is to provide a complete container or carrier for displaying and carrying bottled beverages and the like which may be formed with a minimum of waste in a single die cutting and scoring operation from a sheet of compressed paper stock such as cardboard.

A further important object of the invention is to provide a container or carrier which may be manufactured inexpensively, and which may be shipped flat to the point of sale and assembled there in an easily executed folding operation; and which is sturdy and durable in construction without adding reinforcing members.

The container of the present invention is formed from a blank comprising, in general, an elongated generally rectangular sheet of relatively stiff foldable material, a slot extending transversely of said sheet about midway between the ends and stopping short of the sides thereof, a transverse opening on each side of said slot and adjacent thereto, a transverse generally rectangular panel defined by transverse and longitudinal scored lines between each opening and the adjacent outer ends of said rectangular sheet of foldable material, a narrow portion at each end of said foldable sheet of the blank being of a width only slightly less than the length of said transverse slot, a transverse opening in each of said narrow end portions, and scoring across each of said end portions connecting the sides of the sheet with openings in the ends of the blank.

An understanding of the manner in which the above and other objects of the invention are attained may be had from the following description, reference being made to the accompanying drawing in which:

Figure 1 is a top plan view of a sheet of rela-

tively stiff foldable material such as cardboard die cut and scored ready for folding to form the carton or carrier of the present invention;

Figure 2 is a perspective view of the carton formed from the sheet illustrated in Figure 1;

Figure 3 is a fragmentary view of a modification of the invention.

Like reference characters refer to like parts throughout the specification and drawing. In the drawing, the lines along which the blank is die cut are indicated by full lines, and the lines along which the blank is scored are indicated by dotted lines.

The blank illustrated in Figure 1 is formed of relatively stiff foldable material, for example, strong compressed paper stock such as relatively heavy cardboard and is of generally rectangular shape. The material may be coated or impregnated with wax or other suitable material to make it resistant to moisture.

A transverse slot 10 is cut in the blank midway of its ends. This slot 10 extends towards but stops short of the sides of the blank and is of a width approximately twice the thickness of the material of which the blank is formed. The slot is defined by transverse die cut lines joined by short longitudinal die cut lines.

A transverse opening 11—11a is formed on each side of and adjacent to the slot 10, being separated from the slot by a relatively narrow strip of material. Each opening 11—11a extends transversely of the blank towards but stopping short of the sides. Each opening is preferably of a width slightly greater than the diameter of the contents, such as a soft drink bottle, which the carton is designed to receive. Also, the ends of each opening are preferably rounded and one edge may be incompletely severed so that the died out piece remains partially attached to the side of the container.

A rectangular shaped transverse panel 12—12a is defined by transverse and longitudinal scored lines approximately midway between each opening 11—11a and the adjacent ends. A scored line 18 extends at an angle outwardly of the panel from each corner defined by the point of intersection of the transverse and longitudinal scored lines to the adjacent outer edge of the blank to permit folding and to provide reinforcements for the load carrying bottom trays when the container is set up, as described in detail hereinafter.

Each end portion 13—13a of the blank is restricted in transverse section for a short distance 50 of its length. These narrowed end portions are

of a width only slightly less than the length of the transverse slot 10 and terminate preferably in rounded ends 14-14a to form, with the transverse openings 15-15a, carrying handles.

A transverse opening 15-15a is provided in each narrowed end portion and is defined by an outer cut or scored line 19-19a adjacent to the rounded end and is preferably formed in an arcuate curve connected at its ends to an inner scored line 20-20a which extends transversely of the blank and connects the sides of the sheet with the opening. The piece of material which is die cut to form each opening 15-15a may be cut out completely and discarded at the time of forming the blank, or it may be partially cut out and partially attached by merely scoring along one or more of its boundary lines. This latter modification is preferred in that it permits the handle portions to be folded over flat when assembled to provide a surface upon which another container may be superimposed to save space and to provide an attractive display.

In the preferred embodiment of the invention illustrated in Figure 1, the upper surface of the blank is considered as forming the interior surface of the finished container and the under-surface normally would be attractively coloured and printed to display and advertise to their best advantage the particular wares in association with which it is to be used.

In assembling the container, each end of the blank is folded along the transverse scored lines forming the panels 12-12a and the end portions 13-13a are passed through the slot 10 to form the handles by means of which the container is carried. The transverse panels 12-12a are folded along their transverse and longitudinal scored lines to form the bottom load carrying trays, and folded along the scored lines 18 to form the end reinforcing members.

Preferably, the container is formed of relatively strong, rigid, paper board, waxed or impregnated or otherwise treated against moisture absorption and of sufficient strength to carry safely the loads to which it is exposed. However, if desired, the trays formed by the panels 12-12a may be reinforced by securing the corners defined by the lines 18 to the adjacent wall surfaces, such as by staples 16, as illustrated in Figure 3.

Also, if desired, a false bottom 17 may be inserted after the carton has been assembled to absorb any moisture which may drip from the articles to be carried, particularly if bottled beverages from a refrigerator are inserted into the carton and the carton is formed of material which would tend to absorb moisture.

The container or carrier of the present invention has a number of important advantages.

The blank may be formed in a single operation, from a single sheet of material, with a minimum of waste and without the need of providing any extraneous reinforcing members, such as nor-

mally are required in similar articles of the prior art. It may be distributed to the user in sheet form and thus permits important savings in the cost of shipping to the point of sale, and is quickly and easily folded to form a container in which the wares may be prominently and attractively displayed and carried. In use, it is of a sturdy construction and is adapted to carry a relatively heavy load without inconvenience.

It will be understood, of course, that modifications in the preferred embodiment of the invention described and illustrated herein may be made without departing from the scope of the invention as defined by the appended claims.

What I claim as new and desire to protect by Letters Patent of the United States is:

1. A container blank comprising an elongated generally rectangular sheet of relatively stiff foldable material, a slot extending transversely of said sheet about midway between the ends and stopping short of the sides thereof, a transverse opening on each side of said slot and adjacent thereto, a transverse generally rectangular panel defined by transverse and longitudinal scored lines between each opening and the adjacent outer ends of said rectangular sheet of foldable material, a narrow portion at each end of said foldable sheet of the blank being of a width only slightly less than the length of said transverse slot, a transverse opening in each of said narrow end portions, and scoring across each of said end portions connecting the sides of the sheet with the openings in the ends of the blank.

2. A container blank comprising an elongated generally rectangular sheet of relatively stiff foldable material having straight unbroken parallel sides, a slot extending transversely of said sheet about midway between the ends and stopping short of the sides of said sheet, a transverse opening on each side of said slot and adjacent thereto, a transverse rectangular panel defined by transverse and longitudinal scored lines between said openings and the ends of said sheet of foldable material, scored lines extending in parallel spaced relation across the width of the sheet of material and other scored lines removed from but meeting the first mentioned scored lines but being disposed inwardly from the edges of the blank, and diagonal scored lines extending from the edge of the blank at an angle and intercepting the first and second mentioned scored lines.

LEO MORGAN.
